ATTORNEY

UNITED STATES PATENT OFFICE

JAMES S. THELEN, OF CHICAGO, ILLINOIS, ASSIGNOR TO GENERAL ELECTRIC X-RAY CORPORATION, OF CHICAGO, ILLINOIS, A CORPORATION OF NEW YORK

ANODE

Application filed July 30, 1928. Serial No. 296,357.

The present invention relates to X-ray tubes, or to other tubes in which there is an anode which may, during operation, become heated, and has particularly to do with the construction thereof and the provision of a novel means for dissipating the heat from such anode.

Included in the objects of the invention are the following provisions:

10 A novel and unique means for cooling the anode of an X-ray tube;

A new means for constructing the anode of an X-ray tube;

15 Means for grounding the anode of an oil-immersed tube or the like;

An oil-immersed tube in which the anode is grounded to the tank containing such tube and its energizing equipment;

20 The employment of a tank for an oil-immersed X-ray tube as a means for absorbing the heat from the anode of a tube and for a radiating such heat to the atmosphere;

The provision of additional means in such a structure for the absorption of heat; and

25 Removable and replaceable heat-absorbing parts in connection with an anode for an X-ray tube.

These, and such other objects as may hereinafter appear, are obtained by the novel 30 construction, arrangement, and combination of elements disclosed in the accompanying drawing illustrative of one embodiment of the invention, which embodiment is illustrated in a single sheet of drawing accompanying this application and hereby made a part hereof, and in which

Figure 1 is a diagrammatic view showing the circuit and the apparatus, the tube and tank both of which are in section;

40 Figure 2 is an enlarged view of an anode for a tube made in accordance with the invention;

Figure 3 is a section along the line 3—3 of Figure 2.

45 One of the great difficulties encountered in X-ray tube operation because of the tremendous heat produced thereby is the dissipation of such heat. This comprises a problem which annoys all X-ray engineers. The 50 question of whether the power input to X-ray

tubes can be increased and the field of utility of X-ray equipment thereby widened depends in a great measure on how successfully this problem can be solved. With the introduction of the oil-immersed type of tube, the importance of this problem has been increased and as is herein indicated, one of the objects of the invention is to provide a structure for this type of X-ray tubes which will facilitate heat-absorption.

In carrying out the invention, and in the illustration thereof, an oil-immersed type of tube is described and shown, but of course the invention is not limited to such type of tube or to X-ray tubes.

One of the primary considerations for the use of the present invention is the grounding of the anode of the X-ray tube to the tank in which the X-ray tube and its energizing equipment is enclosed. By so doing, it becomes feasible to further use the tank, which is generally of aluminum or of such similar material of high heat conductivity for a means of absorbing heat from the anode of the tube and for radiating this heat rapidly to the atmosphere.

In addition to providing means whereby the tank assists in the absorption of heat, the anode of the tube is of a particular type comprising a removable section which may be replaced from time to time, so that the heat which passes into the shank of the anode may be absorbed by a mass of heat-absorbing material at the outer end of the shank of such anode.

In this fashion, a tube which has already been heated to the limit, may be very rapidly cooled by the removal of the heated heat-absorbing section of the anode thereof and the replacement of such section with one the temperature of which is lower than that of the anode. It is therefore possible to quickly reduce the temperature of the anode of a tube if the use of the machine is necessary subsequent to the time the anode thereof has been run until nearly to the point of maximum allowable temperature.

Like reference characters are used to designate similar parts in the drawing and in the

description of the invention which is herein made.

A tank 10 for enclosing an X-ray tube and its energizing elements is shown. This is generally made of aluminum or of other material of high-heat conductivity.

Said tank 10 has a cover 11 which has a window for the passage of X-light. Within the tank 10 is the tube 12, the anode of which is of special construction to be referred to shortly. Such anode is designated 13 and has a threaded outer end, while the cathode of the tube is marked 14. The bulbous portion of the tube 12 is designated 15, and at the end of the anode 13, is a laterally extending threaded stud 16 on one of the walls of the tank 10 for the purpose of engaging the threaded end of the anode 13 and supporting the X-ray tube 12 in position within the tank

10. The anode 13, as shown, has a hollow stud, the hollow portion being designated 17.

Upon the walls of the tank 10 is a socket 18, the opening in which registers with the opening in the threaded stud 16 and in this socket is a replaceable heat-absorber unit 19 which is adapted to be screwed into position therein to cooperate with the anode 13, filling the hollow portion 17 of the stem of said anode, said heat-absorber 18 having a large external head supplied with a handle 20 which is separated from the main body of the head by heat-insulating members 21 in order to prevent the handle 20 from becoming excessively heated.

Extending from and about the tank 10 are parallel radiating fins 22, such fins being common to oil-immersed X-ray units.

A source of power 23 is shown in Figure 1. 40 This is connected to a main switch 24 which in turn opens and closes the electrical circuit to an auto-transformer 25 having an adjustable tap 26 for regulating the voltage across the primary of a high tension transformer, later to be mentioned.

Resistance in series with the primary of a filament transformer for regulating the voltage across the primary of such filament transformer is indicated 27.

30 The primary of the above referred to high tension transformer is designated 28, and its secondary 29, while the primary of the filament transformer mentioned is 30, its secondary being designated 31.

55 Between the secondary 29 and the tank 10 there is a ground connection 32, and there is also a connection 33 between the secondary 29 and the secondary 31. The conduits to the filament of the X-ray tube 12 are designated 34, one of these of course providing electrical connection for the high tension current impressed upon said tube 12, the tank 10 itself providing the other conduit for such high tension current.

60 65 In its regular operation, the tube 12 per-

forms in the present apparatus just as it would in any other oil-immersed apparatus. The high tension circuit is through the cathode and the anode, the anode being electrically connected to the tank 10 which forms a conductor or part of the circuit to one end of the secondary 29 of the high tension transformer, the other end of the secondary of said transformer, as previously indicated, being connected to the cathode through the agency of one of the conduits 34 from one end of the secondary of the filament transformer. The circuit is otherwise conventional.

Examination of Figure 2 will disclose the 30 stud 16 comprising a part of the casing 10 and to which the anode 13 of the tube 12 is adapted to be secured.

Intermediate the wall of the tank 10 and the end of the anode is a washer 35 adapted 35 to facilitate the sealing of the aperture intermediate the tube 12 and the casing 10, and also making provision for the necessary rotation of the tube 12 until the target thereof is properly disposed to project X-light 90 through the window in the cover 11 of the casing.

The hollow portion 17 of the anode 13 extends into close proximity to the tungsten button 36 upon the anode 13, such button 95 being very clearly shown in the cross sections of both Figures 1 and 2.

The cooling member comprises a shank adapted to completely or substantially fill the hollow space 17, an enlarged threaded portion adapted to be inserted into and be rotated into position in the socket 18 of the tank, a head, and a handle insulated from such head.

The reason for employing the enlarged 105 head shown is to give to the removable section 19 of the anode 13 a greater heat-absorption capacity, it being obvious that the metal of the removable section 19 of the anode should be integral and of a metal of 110 great capacity with respect to heat-absorption.

During the operation of the tube 12 and without disconnecting the electrical connections which supply energy thereto, it is possible to remove one of the cooling members 19 which has become heated and to substitute therefor a second member 19 which has been pre-cooled. By using a plurality of such members 19, and keeping the members to be 120 inserted at a low temperature before insertion, it is possible to operate a tube 12 almost continuously without any danger of overheating. The advantages of such a structure over a water-cooled or mercury-cooled system reside in the proposition that there are no external pipes to be installed, that there is no great weight attached to the cooling system, and that the present apparatus is 125 particularly adapted to be used in a portable 130

outfit where mercury cooling or water-cooling probably would be impracticable. A half dozen of such cooling instrumentalities 19 would be all that is required except under the most extraordinary circumstances; in fact, a half dozen removable sections 19 for the anode 13 would probably suffice for each and every emergency to which the tube in service may be subjected.

5 I claim:

- 10 1. An X-ray apparatus comprising an X-ray tube having a threaded section, a tank disposed about said tube and having a threaded lug to engage the threaded portion of said tube, and a cooling element comprising a part of the anode of said tube and adapted to be removed from said tube through the walls of said tank.
- 15 2. In an X-ray system, a casing of relatively large capacity for heat absorption, an X-ray tube in said casing, an anode in said tube, means for energizing said tube and heating said anode, means projecting from said anode through said casing for conducting the heat of said anode to said casing, and means associated with said casing for dissipating such conducted heat by radiation.
